UNITED STATES PATENT OFFICE.

WILLARD H. BROCKWAY, OF NEEDHAM HEIGHTS, MASSACHUSETTS

CARTRIDGE SYRINGE.

Application filed October 16, 1925. Serial No. 62,793.

My present invention relates to improvements in cartridge type hypodermic syringes, as used in dental and surgical practice. It is its object to improve the construction of 5 such syringes making them more effective and convenient in operation, free from the necessity of frequent repairs, and better adapted to practical and economic manufacturing.

10 More particularly, my invention involves improvements over the prior art in syringes of the breech loading cartridge type, in that it makes it at once possible for the surgeon or dentist to remove or separate the head 15 or breech of the syringe, from the cylindrical holder which contains the cartridge, and clean the syringe mechanism as may be necessary from time to time, as well as to make minor repairs.

20 Not infrequently the glass cartridge, used to contain the medicament breaks at the time of the injection, causing the novocain, or serum to be spread over the spring and other internal parts of the syringe, causing annoyance and delay to the doctor and frequently very great inconvenience to his patient. After an accident of this kind, if the syringe is not cleaned immediately, the medicament may solidify and cause the moving 25 parts of the syringe to stick and often to become inoperative. In emergencies requiring the use of certain drugs, time is an element of very great importance. With the use of the cartridge syringe, embodying my 30 invention, delays and annoyance now of frequent occurrence will be entirely eliminated.

The economic advantages accruing from 35 my invention, will be apparent, when it is pointed out that frequently when a syringe 40 becomes stuck, or "frozen", it becomes necessary to return it to the factory to be repaired, as there has been no provision for detaching or disassembling the breech. A syringe embodying my invention makes it possible 45 for the surgeon or dentist to detach the breech and open it up without tools by a simple manipulation of the parts.

One of the most frequent causes of breaking of cartridges is due to the variations in 50 the diameter of the commercial glass used in making cartridges for containing medicament. A small cartridge may drop to one side of the cartridge holder of the syringe, thereby getting out of line with the piston 55 and causing the piston head to strike on the edge of the glass cartridge, instead of

striking squarely on the rubber stopper. My invention provides a sufficient range to automatically center cartridges, even if they vary as much as two millimeters in diameter. 60 Furthermore as these cartridges must be produced at a low cost, the cutting to length, varies considerably; frequently as much as two millimeters. My invention provides for a syringe structure, so adaptable, that variations in length as well as in diameter are 65 automatically cared for.

There is another important phase of my invention resultant from the principles involved. In many uses of the hypodermic, 70 particularly in oral work, it is of the utmost importance that vision be obscured as little as possible and that the manipulation of the syringe be made so convenient that the operator can locate his needle point 75 with his hand in any convenient position and yet be able by a simple extension of the thumb definitely and positively to engage the plunger handle to discharge the syringe. One of the practical factors involved in such a manipulation of the syringe 80 has been the undesired movement of the plunger, as for example, by gravity, where the syringe was held in inverted position. It is therefore of very great importance 85 that the plunger be very slightly frictionally controlled without actually interfering with the freedom of operation of the hypodermic.

To make this all clear, I have shown in the accompanying drawings a form of syringe 90 well adapted to commercial production and well received by the profession. Throughout the specification and drawings like reference characters are employed to indicate corresponding parts, and in the 95 drawings:

Fig. 1 is an elevation of a filled syringe.

Fig. 2 a fragmentary view of the same with top opened for refillment.

Fig. 3 a sectional detail of the head.

Fig. 4 a view with the parts unlocked.

Fig. 5 a sectional fragmentary view of the head.

Fig. 6 an exaggerated fragmentary section, and

Fig. 7 a diagrammatic illustration of the spring.

Considering, as illustrative, the construction shown, we may refer to Fig. 1 as showing one of my syringes of a generally 110 accepted type. Generally, the construction comprises a tubular frame 1 having a lower

end 1¹, and an upper end 1². At the lower end a cap 2 is forced on by a die process making a member, unaffected by heat and having a threaded lead 2¹ to receive a needle 3 which may be clamped on by a cap 4. This, with the exception of the swedged or die fitted cap is old and well adapted in our practice.

At the upper end my invention provides 10 simple but very important factors. The head which constitutes a breech block for the syringe has usually in practice been pivoted on screws. These have proven serious factors of inconvenience. Further, 15 the head has not been capable of dismemberment sufficient to permit the freeing of the parts in case of corrosion or sticking of the plunger 9. I therefore provide a free and easy assemblage of parts by reason of 20 which all may be kept clean and clear.

Reverting to the head structure, I may describe the form shown as comprising a head cap 5 having an extension 6 and depending ears 7. These ears 7 have a pivot 25 recess 7¹ and a curved lead 7². This permits the connection of the head or cap by a bayonet-like attachment and a similarly ready disconnection for cleaning or sterilization. The head 5 supports on a shoulder the fin- 30 ger piece 6 which is free to turn on the head below the dome 8. The dome 8 is a sleeve, die forced on the cap extension 5 so as to swage its upper edge 8¹ into a groove near the upper end of this member.

35 The plunger stem 9 having the cross bar 11 of usual form works through the head. At its lower end it has a piston head 9¹ adapted to engage the cork C to expel the charge S.

40 About the plunger 9 is a spring 10. At its lower end it bears on a block 12 through which the plunger passes. This block under the action of the spring enters the end of the frame and bears on the end of the tube T. 45 The lower face of the block 12 is formed with a tapered or bell shaped recess 12¹ which centers and aligns the cartridge tube T in the casing so that the piston end 9¹ will not break the tube in case it is under- 50 size. The block 12 therefore constitutes a breech block or lock holding the head in position and the plunger in alignment, and at the same time holding the tube or cartridge in position.

55 To refill, the plunger is retracted until its piston end 9¹ lifts the block 12 out of the frame end. The head may then be swung on the pivots 13 which are engaged in the recess 7¹. These pivots 13 are struck outwardly from the frame so as to provide solid rigid members on which the head may turn.

Reverting now to the spring 10 it is to be carefully noted that in addition to its interlocking urge upon the breech block 12 60 it has another very important function.

As has been previously pointed out a hypodermic very frequently must be operated with a very considerable degree of technique, one feature of which is the "finding" of the handle 11 by the thumb without glancing from the needle point. 70

The piston head 9¹ is supposed to have been brought against the stopper C and the operator has gaged his thumb movement accordingly. If, however, as when the syringe 75 is inverted, the plunger has dropped back, the reach to the handle 11 is longer and there is lost motion in the return stroke.

By my spring 10 I am able to get a delicate but definite control on the stem 9 in any position. I accomplish this by assembling the spring 10 under a slight compression. That is to say before assembling the terminal turns of the spring fit the stem 9 85 loosely.

As shown the spring is a spiral of double conic common base type. The central zone is at all times free from the stem 9. Upon compression as when in the position shown in Fig. 3 the end coils or turns 10' are forced 90 into frictional contact with the stem 9 as indicated diagrammatically in Fig. 7.

In Fig. 7 the open lines indicate the spring as free or not under compression. The black dots are intended to indicate in an exaggerated way the positions of the coils or turns when under compression. 95

It will thus be seen that when positioned as in Fig. 3 the stem 9 is under a very slight 100 but definite friction. When the breech block is withdrawn to swing or remove the breech as in Fig. 4, the spring 10 comes under further compression but at that phase the stem 9 is wholly withdrawn and the syringe is not expected to be in its period of operative 105 or medical use. When "loaded" as in Fig. 3, the spring 10 is under the proper compression to give the right friction for operative control. This function of the spring 110 10 is a most important feature. It happens to have the additional function of locking the breech block 12 but its control of the plunger is of great importance in professional manipulation.

While the particular syringe shown is 115 one of approved commercial design it is to be understood that the features of my invention may be otherwise embodied in whole or in part.

What I therefore claim and desire to secure by Letters Patent is:

1. In a syringe, a tubular shell having an open breech at one end, and adapted to contain a cartridge, a displaceable head normally aligned with said shell, a breech block in said head, a piston slidable through said head and breech block and adapted to urge said block into the open breech of said shell, and a trunnion bearing pivot connection between said shell and head permissive of the 120 125 130

displacement of the head and comprising interengaging members disengageable only in the displaced position of the head.

2. In a syringe of the class described, a cartridge frame comprising a tubular shell, a head detachably pivoted thereto, whereby the head may be disengaged from the frame, a follower in the head, a piston stem passing through the follower, and a coiled spring disposed about said piston and having its ends adapted to frictionally engage therewith and normally tending to enter the follower within the frame end.

3. In a syringe of the class described, a cartridge frame comprising a tubular shell, an integral pivot point struck outwardly from the shell adjacent the top thereof, a plunger head having a pair of depending ears, each of said ears having a pivot recess 20 and a lead groove thereto, whereby the head may be disengaged from the frame.

4. In a syringe of the class described, a cartridge frame comprising a tubular shell, an integral pivot point struck outwardly 25 from the shell adjacent the top thereof, a plunger head having a pair of depending ears each of said ears having a pivot recess and a lead groove thereto, whereby the head may be disengaged from the frame, a follower in the head, a piston stem passing through the follower, and a coiled spring disposed about said piston stem and having its ends adapted to frictionally engage therewith and normally tending to enter the follower 35 within the frame end.

5. In a syringe, a tubular shell adapted to contain a cartridge, pivots on the shell adjacent the top thereof, a recessed head normally aligned with said shell and having 40 a pair of depending ears provided with pivot recesses and lead grooves thereto to said recesses adapted to receive said pivots and permitting complete detachment of the head and shell by first swinging the shell laterally on its pivots and then drawing it 45 laterally from between said ears.

6. In a syringe of the class described, a cartridge frame comprising a tubular shell, a pivot on the shell adjacent the top thereof, a plunger head having a pair of depending ears, each of said ears having a pivot recess and a lead groove thereto, whereby the head may be disengaged from the frame, a follower 50 in the head, a piston stem passing through the follower, and a coiled spring disposed about said piston and having its ends adapted to frictionally engage therewith and normally tending to enter the follower within the frame end.

7. In a syringe, a head, a plunger working through said head and a helical spring about said plunger, and compressed longitudinally within said head for frictional grip upon said plunger.

8. In a syringe, a frame having an open

breech, a displaceable head, a breech block in said head and adapted to enter the frame breech, a plunger disposed through said head and block and a compression spring between said block and head and disposed to frictionally grip said plunger when under compression.

9. In a syringe, a recessed head, a breech block therein, a plunger working through said head and a spiral spring surrounding 75 said plunger in the head recess and bearing against said block, said spring frictionally engaging said plunger.

10. In a syringe, a plunger, a conical helix spring normally permitting free movement of the plunger relative thereto, and means whereby the spring may be longitudinally compressed to frictionally grip said plunger.

11. In a syringe, a cartridge frame, a 85 recessed head pivotally mounted on the end thereof, a spring pressed breech block in said head recess and adapted to contact the cartridge end, the face of said breech block having a flaring recess to center a cartridge. 90

12. In a syringe, a cartridge frame adapted to contain a cartridge, and a spring-pressed follower adapted to seat against the adjacent end of a cartridge in said frame, said follower having a flaringly recessed end 95 effective in the seating action of the follower automatically to center the cartridge in the frame.

13. In a syringe, a cartridge frame comprising a tubular shell having an open breech, pivots on the shell adjacent the top thereof, a recessed head having a pair of depending ears provided with pivot recesses and lead grooves to said recesses adapted to receive said pivots and permitting detachment of said frame and head by swinging the frame laterally on its pivots and followed by an endwise withdrawing movement, a spring pressed breech block in the recess of said head and adapted to contact 100 the end of a cartridge mounted in said cartridge frame, a piston stem disposed through said head and breech block, and a coil spring confined between said breech block and the opposite end of said head and adapted frictionally to engage said plunger when compressed and interlockingly to urge the breech block into the open breech of said frame.

14. In a syringe, a frame having an open 120 breech, a head aligned with said frame, a breech block in said head, a plunger disposed through said head and block and a single means for frictionally gripping the plunger and for interlockingly seating the 125 breech block in the open breech of said frame.

15. In a syringe, a piston stem and a normally free spiral spring compressibly engaged therewith to frictionally control the 130

same, and means whereby the spring may be compressed to frictionally engage it with the piston stem.

16. In a syringe, a plunger, and a spring friction member normally permitting free movement of the plunger relative thereto, and means whereby the spring may be longitudinally compressed to frictionally grip said plunger.

10 17. In a syringe, a frame having an open

breech, a head, a breech block in said head, a plunger working through said head and block, a spring cooperative with said plunger and block, and compressed between said head and block to cause it to frictionally grip 15 said plunger and to interlockingly urge said breech block into the open breech of said frame.

In testimony whereof I affix my signature.

WILLARD H. BROCKWAY.
